CLAIM

The ornamental design for a frontal sensor device for neural and mental assessment, as shown and described.

DESCRIPTION

FIG. 1 is a perspective view of the frontal sensor device for neural and mental assessment showing our new design.

FIG. 2 is a front elevational view thereof.

FIG. 3 is a back elevational view.

FIG. 4 is a left side elevational view.

FIG. 5 is a side elevational view.

FIG. 6 is a top view; and,

FIG. 7 is a bottom view.

The broken lines illustrate portions of the frontal sensor device for neural and mental assessment that form no part of the claimed design.
